UNITED STATES PATENT OFFICE.

VICTOR HANSON, OF RICHMOND, VIRGINIA, ASSIGNOR OF ONE-HALF TO
JAMES G. WHITLOCK, OF HANOVER COUNTY, VIRGINIA.

AMALGAMATING APPARATUS.

SPECIFICATION forming part of Letters Patent No. 618,938, dated February 7, 1899.

Application filed September 29, 1897. Serial No. 653,505. (No model.)

To all whom it may concern:

Be it known that I, VICTOR HANSON, residing at Richmond, in the county of Henrico and State of Virginia, have invented a new and Improved Amalgamating Apparatus, of which the following is a specification.

This invention, which relates generally to mining apparatus, refers more particularly to a combined ejector or hoist means and amalgamating devices of a very simple and economical nature, which can be easily manipulated and which will effectively serve for their intended purposes; and such invention consists in the peculiar construction, novel combination, and arrangement of parts, such as will be first described in detail, and then be specifically pointed out in the appended claims, reference being had to the accompanying drawings, in which—

20 Figure 1 is a side elevation of my improved mining apparatus, parts being in section. Fig. 2 is a top plan view thereof. Fig. 3 is a transverse section of the riffle-trough, taken on the line 3 3 of Fig. 1. Fig. 4 is a detail section taken on the line 4 4 of Fig. 2. Figs. 5 and 6 illustrate a modified form of hoist for lifting the spoil to the riffle-box. Fig. 7 is a detail sectional view of the pivotally-mounted dead-water vat. Fig. 8 is a detail view of the removable washer. Fig. 9 is a detail view of the cap-plate. Fig. 10 is a detail view of the removable cap. Fig. 11 is a detail view of the rotary digger.

Referring to the accompanying drawings, in which like numerals and letters indicate like parts in all the figures, 1 indicates the amalgamating or collecting portion of my improved mining apparatus, which consists of an upper and lower riffle-box 1^a and 2, which incline 35 downward in reverse directions and connect in the manner presently more fully described. The boxes 1^a and 2 are each formed of a plank bottom 3 and sides 3^a, the front or feed end of the upper box being open to receive the discharge end of the hoist-pipe 26 or sluice-box. The bottom 3 of each riffle-box has a series 40 of concave transverse grooves 5, in which seat the mercury-pipes 6, the ends of which project beyond the sides 3^a to receive the unions 6^a 6^b, as clearly shown in Fig. 3, which serve to securely hold the sides and bottom

planks clamped together. Each pipe 6 has an inlet-pipe 7 provided with a valve 7^a, and such inlet-pipes 7 are suitably connected to a feed-pipe 8, which connects at one end to a 55 feeder-trough 9. Each of the pipes 6 is cut away at the top at points between the sides 3^a 3^b of the boxes, so as to produce a series of transverse troughs 10, the lower edges 10^a of which project in practice about one-fourth of 60 an inch above the bottom plank 3, (see Fig. 4,) which produces riffles at the troughs 10, so that when the water and sand strike such edges 10^a a reaction or rotary motion is effected which keeps sand in motion, and therefore causes the mineral to come in contact with the mercury held in the troughs, while the larger particles rise over the riffles and pass off with the water-current. The outer ends 65 of the pipes have valved discharge-nozzles 11, 70 which empty into strainers 11^a 11^b, secured to the adjacent side of the box, and which consist each of an oblong box 12, having a strainer-cloth 12^a or other suitable foraminous material at the top, the upper strainer 75 11^a emptying into the lower strainer 11^b, which in turn discharges into a collecting-trough 13.

So far as described it will be readily seen that the supply of mercury to the different riffle-troughs can be regulated at will and the 80 mixed mercury and amalgam drawn off from the troughs 10 and discharged into the strainers, it being obvious that the amalgam will be caught by the straining-cloth, while the quicksilver passes through into the strainer-boxes and down into collecting-trough 13, from whence the quicksilver, together with such fine gold as may have passed through the strainer-cloth, is dipped back into the feeder-trough. In practice the supply-pipe 85 90 is kept filled with quicksilver, so that when the riffle-troughs are emptied a new supply is always on hand, thereby making it unnecessary to wait for filtration.

The discharge end of the upper riffle-box 95 terminates in a grating 15, through which the current-water and finer particles pass onto the receiving end of the lower riffle-box, the larger particles—stones and boulders—passing over such end onto a dump-chute 16. 100 The current-water, with the grosser material, after leaving the bottom riffle-box empties

into a collecting-vat 18, in which is held still water, which allows the fine flour-gold to settle therein.

The dead-water tank has an overflow-pipe 18^a at the side opposite the inlet side, which empties into a water-tank 19, which in practice has a suitable feed or supply pipe provided with a suitable automatic valve. (Not shown.) The dead-water tank is of such a width in the direction of the flow of material from the riffle-boxes that there will be no perceptible current to carry the fine mineral over the discharge end with the boulders and refuse material, which dumps between the dead and feed water tanks. 20 indicates a pump of any suitable character, which has a suction pipe or pipes 21 projected into the feed-water tank. 22 indicates the discharge or force pipe of the pump, which in the form shown in Fig. 1 connects with a union member 23, having a reduced nozzle 24, which ejects the pump-flow over the inlet-opening 25, with which connects a lift-pipe, through which the sand or spoil is raised by suction into the lift-pipe 26, which discharges into the feed end of the upper riffle-box, as shown. By this arrangement of parts it is manifest the water forced out by the pump is ejected through the nozzle 24 with sufficient force to raise the spoil from a sluiceway or sand-bank. It will be also readily seen that the water-current which passes over the riffle is carried back into the water-feed tank, from which it is again drawn out by the pump, forced through the ejector, back over the riffles, thereby continuously using the same water or as much thereof as is necessary to keep up the necessary water-supply to accomplish the desired results. While I prefer to combine the amalgamator portion of the apparatus with a force-lift, as described, such amalgamator under certain conditions may be used in conjunction with an ordinary sluiceway, and the latter will then be arranged to empty into the upper riffle-box, as will be readily understood. When thus used, the dead-water vat is preferably supported upon a pivotal bearing, as indicated in Fig. 1, and has connected therewith an eccentric rocker-disk 28, mounted on a shaft having suitable drive connections. (Not shown.) In this latter form the dead-water vat has its bottom provided with a series of pockets or flutes 29 for the quicksilver and fine mineral to lodge in during the vibration of the vat.

In Figs. 5 and 6 I have shown a modified form of lift and ejector means for lifting and feeding the spoil from a sluice or for serving as a sand pump or dredge, and such construction comprises a force-pipe I, having a pendant branch I', provided with a valve L, which terminates at the bottom in an ejector-nozzle E, which discharges into the lift-pipe I², past the suction-opening M, to which the sluice-way or hopper feeds. The upper end of the pipe I² terminates in a discharge-pipe J, which leads the material to either the amalgamator

or other separating means. When the conditions are such that the pipe I² must be of considerable length, greater than the 70 ejector E can successfully lift the spoil, such pipe I² is also connected with pipe J by a supplemental pipe I³, having an ejector-nozzle E' and a valve L'. The lower end of pipe I² has an annular flange II to receive a detachable section, in the lower end of which is journaled a rotary digger G, the shaft of which has a drive-pulley g to receive the drive-belt g', driven by counter-shaft g². K indicates a cap-plate adapted to be fitted on 80 the flange of section II when the digger is removed. D indicates a washer which is secured over the nozzle E, when the lift is used to take up through the suction-opening M, to prevent any of the material dropping out 85 at the bottom. When the digger is used, the washer D is removed and the suction-opening is held covered by the cap B. When the latter form of lift devices is used and the pipe I² is of a short section, the valve L' is 90 closed and the ejection effected through the water force passing through nozzle E. When the force passing through such nozzle is insufficient to raise the spoil, the valve L' is opened to allow a part of the water force to 95 pass through nozzle E'.

In practice the pipe I is connected to the pump by a suitable universal joint to admit of the lower end being placed at any direction from the pump.

From the foregoing description, taken in connection with the accompanying drawings, it is thought the complete operation and the advantages of my invention will readily appear to those skilled in the art to which it 105 appertains.

Having thus described my invention, what I claim, and desire to secure by Letters Patent, is—

1. An apparatus of the class described, comprising the upper and lower reversely-inclined riffle-boxes, transverse troughs having discharge-nozzles outside of the box, the reversely-inclined strainers located outside of the riffle-boxes and extending longitudinally 115 of the same and arranged beneath the discharge-nozzles, a collecting-chamber located at the lower end of the lower strainer, a tank receiving the water from the lower riffle-box, a pump located above the tank and having a 120 take-up pipe extending into the same, a feed-pipe depending from the pump, and a lift-pipe extending from the feed-pipe to the upper riffle-box, substantially as described.

2. An apparatus of the class described, comprising the upper and lower oppositely-inclined riffle-boxes, transverse troughs having discharge-nozzles outside of the boxes, the strainers located outside of the boxes and extending longitudinally of the same at an inclination and arranged beneath the discharge-nozzles, a collecting-chamber located at the lower end of the lower strainer, a vat receiving the water from the lower riffle-box, a dead-

water tank having an overflow-pipe connected with the vat, a pump having a depending take-up pipe extending into the tank, a feed-pipe depending from the pump, and a lift-pipe extending from the feed-pipe to the upper riffle-box, substantially as described.

3. In an apparatus of the class described, the combination of a riffle-box having a flat inclined bottom with transverse seats, a series of transverse pipes arranged at intervals and held on such seats and projected through the sides of the box, one end having valved inlets, the other valved discharge-nozzles, said pipes having their upper faces cut away to form troughs, the edges being projected above the bottom of the box at the lower sides of the troughs to agitate the water, a mercury-feed common to all the inlet ends, and a longitudinal strainer located outside of the box and arranged beneath the discharge-nozzles, substantially as described.

4. In an apparatus of the class described, the combination of a riffle-box, a series of

transverse troughs having discharge-nozzles outside of the box, a strainer located outside of the box and extending longitudinally of the same at an inclination and arranged beneath the discharge-nozzles, and a collecting-chamber located at the lower end of the strainer substantially as described.

5. In an apparatus of the class described, the combination of an inclined riffle-box, a series of troughs having exterior discharge-nozzles at one side of the box, a mercury-feed trough located at the other side of the box and connected with the said troughs, an inclined longitudinal strainer arranged outside of the box at one side thereof beneath the nozzles and composed of an oblong box provided with a foraminous top, and a collecting-chamber at the lower end of the strainer substantially as described.

VICTOR HANSON.
